UNITED STATES PATENT OFFICE.

CHARLES H. RUST, OF NEWARK, NEW JERSEY.

AUTOMOBILE LOCK.

1,424,262.

Specification of Letters Patent. Patented Aug. 1, 1922.

Application filed April 13, 1921. Serial No. 461,170.

To all whom it may concern:

Be it known that I, CHARLES H. RUST, a citizen of the United States, and a resident of Newark, in the county of Essex and State of New Jersey, have invented new and useful Improvements in Automobile Locks, of which the following is a specification.

This invention relates in general to valve locks and actuating devices for pipe lines, and more particularly to a lock for controlling the fuel or fluid pressure supply for mobile power plants or engines, such for instance as are used in motor vehicles, to prevent unauthorized use or theft thereof.

The objects of the invention are to provide a lock of the character described embodying novel features of construction adapted to be interposed in a pipe so that the lock cannot be tampered with or manipulated in any other than the proper manner without breaking or causing a leak in the pipe line; to provide such a device comprising a gasket-like member adapted to be connected between the flanges of pipes in a line and having a lock embodied and housed therein and connected to a valve controlling the opening in said gasket-like member, and improved means for retaining the valve in open position to prevent closing thereof by vibration; to provide stop means for limiting movement of the valve to full open and closed positions and to indicate when the valve is fully open or fully closed, and to obtain other results and advantages as may be brought out by the following description.

Referring to the accompanying drawings, in which like numerals of reference indicate the same parts throughout the several views,

Figure 1 is a side elevation of a valve lock constructed in accordance with my invention, showing the same interposed and connected between a carburetor and the intake manifold of an automobile engine;

Figure 2 is a vertical longitudinal sectional view through the device taken on the line 2-2 of Fig. 3;

Figure 3 is a transverse sectional view taken on the line 3-3 of Fig. 2;

Figure 4 is a sectional view taken on the line 4-4 of Fig. 2, portions of the lock being shown in elevation;

Figure 5 is a detached perspective view of one of the plates for connecting the valve to the lock;

Figure 6 is a similar view of another of said plates;

Figure 7 is a perspective view of the one of said plates which directly connects with the valve, and

Figure 8 is a detached perspective view of the closure plate between the fuel passage of the device and the controlling lock and actuating mechanism.

In the embodiment of the invention shown on the drawings the reference character A designates a gasket-like body portion or member which is adapted to be interposed between the flanged ends of pipes in a pipe line, the said member being provided with a transverse passage 1 for the fluid or fuel and a pair of oppositely arranged bolt holes 2 to receive bolts for connecting the member in a pipe line. In Figure 1 of the drawings I have shown the device connected between the flanges 3 and 4 of a carburetor and an automobile intake manifold by means of bolts 5.

The member A is provided at one side thereof with an integral lateral extension 6 formed with an opening 7 to receive the casing of a lock B which is of a usual construction and includes a rotatable member or barrel C, such as is common in cylinder locks. The rotation of the barrel may be controlled by any suitable mechanism such as pins which lock the barrel against rotation and are adapted to be actuated by a key D for permitting the barrel C to be rotated. The opening 7 communicates at its inner end with a substantially rectangular recess 8 adapted to receive the mechanism for connecting the barrel C of the lock to a butterfly valve 9 and actuating the same. The recess 8 in turn communicates with the passage 1 which is of a diameter slightly greater than that of the butterfly valve 9.

The casing of the lock B is rigidly secured to a plate E secured in the base of the recess 8, the said plate serving to hold the casing of the lock against rotation and prevent the same from being pulled out of the opening 7. The barrel C of the lock projects inwardly beyond the end of the casing thereof as clearly indicated in Figures 2 and 3, the inner end of the barrel being provided with an integral irregular shaped longitudinal extension F which is adapted to be ordinarily connected to the latch mechanism of a door lock or the like. In carrying out my invention I contemplate the connection of the butterfly valve 9 to the barrel C of the lock whereby rotation of the barrel will

cause actuation of the valve. For this purpose, I provide a plate 10 which is formed with an opening 11 to slip snugly over the end of the barrel C inwardly of the extension F thereon. A second plate 12 is formed with an opening 13 similar in shape to the extension F of the barrel C and which is adapted to fit thereover as shown in Figures 2, 3 and 4 of the drawings, the said plate 10 being rigidly connected to the barrel C by means of screws 14 which pass through the plate into the end of the barrel. A third plate 15 is adapted to be superposed upon the plate 12 and is formed with a polygonal opening 16 to receive the correspondingly shaped end 17 of the shaft 18 of the butterfly valve 9, the opposite end of which is journaled in the member A as indicated at 180. The plate 15 is connected to the plates 12 and 10 by means of screws 19 passing through all of said plates and having a threaded connection with the plate 10. The plate 10 serves as a spacer between the plate E of the lock and the plate 12, and when the plate 12 is secured to the barrel C it will be seen that the barrel is held against outward longitudinal movement in the casing of the lock. It will also be observed that the plates are rigidly connected to the barrel C so as to rotate therewith, and the opening 13 in the plate 12 engaging the projection F on the barrel of the lock will provide a positive and non-slipping connection of the plates with the barrel.

To ensure rotation of the barrel C of the lock in the proper direction and to limit the rotation thereof in order to stop the valve 9 at either a fully open or fully closed position, the plates 10, 12 and 15 are provided with flat sides 20 and 21 adapted to cooperate with the side 22 of the recess 8, the said flat sides 20 and 21 being arranged at substantially right angles to each other. Thus when the valve is in closed position the side 21 is in engagement with the side 22 of the recess 8, and when the barrel C of the lock is rotated to open the valve the other of said sides of the plates will engage the side 22 of the recess; and said sides 20 and 21 will prevent rotation of the barrel in any other than the right direction. To hold the valve in open position to prevent closing thereof by vibration of the engine I provide notches or curved portions 23 at one side of the plates which are adapted to be engaged by one arm of a U-shaped spring 24 secured as by a screw 25 to the base of the recess 8, the opposite end of said spring engaging a wall of the said recess as shown in Figure 4. It will be understood that the valve is held in closed position by the pins in the lock B, and that the key D of the lock cannot be removed from the same until the valve is fully closed. The flat sides 20 and 21 ensure against the valve 9 being rotated

more than 90°, so that the key cannot become locked against removal with the valve in a closed position, the device being thus fool-proof in operation.

To facilitate the formation of the opening 7 and the recess 8 in the body portion A, I construct the same with a removable section 26 on the side opposite said opening which is normally connected to the body portion by screws 27 and dowel pins 28, the said section being removed when it is desired to form the hole 7 and recess 8. To ensure against the section 26 being removed by an unauthorized person for the purpose of disconnecting the valve 9, the dowel pins 28 are provided, and it will be seen that when the member 8 is interposed between the flanges of pipes in a pipe line it will be impossible to remove the section 26 even if the screws 27 are removed by reason of the fact that the dowel pins 28 prevent movement of the section 26 in any direction other than transversely of the member A. To prevent fluid or fuel mixture from passing from the passage 1 through the lock B I provide a plate 29 which is fitted into grooves 30 in the sides of the recess 8 and extends transversely across the same as shown in Figures 2 and 3, the said plate being formed with an opening 31 through 95 which passes the valve shaft 18.

With this construction it will be seen that any attempt to tamper with or break the lock, or disconnect the same from the pipe line will result in a breaking of the pipe 100 line or a leak therein which will prevent operation of the engine. The lock B is entirely housed within the member A so as to be thoroughly protected against injury, and the construction is extremely simple and 105 formed of a minimum number of parts so that there is little possibility of the device getting out of repair. When the valve 9 is in closed position the fuel or fluid pressure supply to the engine through the passage 110 1, is entirely cut off so that operation of the engine is impossible. In case it is desired to lock the automobile and leave the same standing with the engine running for a short time, a sufficient clearance may be provided 115 between the valve and the passage 1 to allow a small amount of fuel to pass therethrough to operate the engine. Any attempt to speed up the engine or drive off with the automobile would be defeated by the restriction in 120 the flow of fuel by the valve 9.

While I have shown and described one possible embodiment of my invention, it will be understood that this is for the purpose of illustrating the principles thereof 125 only, and that many modifications and changes can be made in the detail construction of the device without departing from the spirit or scope of the invention. Therefore, I do not desire to be understood as 130

limiting myself except as required by the following claims when construed in the light of the prior art.

Having thus described the invention, what

5 I claim is:

1. An actuating and locking mechanism of the character described including a casing having an opening therein, a rotatable member mounted in said opening adapted 10 to be connected to a member to be rotated, and a member rigidly mounted on said rotatable member and formed with a pair of substantially flat sides arranged at an angle to each other and adapted to successively 15 engage a side of said opening in the casing to limit rotation of said rotatable member in both directions.

2. An actuating and locking mechanism of the character described including a casing having an opening therein, a lock mounted in said opening and having a rotatable part adapted to be connected to a member to be rotated, a plate rigidly mounted axially of said rotatable part and 25 having a seat on the edge thereof, and spring means mounted on said casing and adapted to engage said plate to hold the said rotatable part against rotation.

3. An actuating and locking mechanism of 30 the character described including a casing having an opening therein, a lock mounted in said opening and having a rotatable part adapted to be connected to a member to be rotated, a plate rigidly mounted axially of 35 said rotatable part and having a seat on the edge thereof, and a substantially U-shaped spring mounted on said casing in said opening between the walls thereof and said plate with one arm in engagement with said walls

of the opening and the other arm adapted 40 to engage said seat on said plate to hold said rotatable part against rotation.

4. A device of the character described including a body portion to be inserted in a pipe line and having a passage therethrough 45 and a lateral recess connected therewith and an opening from said recess through said body portion, a lock including a casing mounted in said opening and having a plate at its inner end secured to the base of said recess, said lock being provided with a rotatable part adapted to be controlled by a key, a valve arranged in said passage for controlling the same, and a second plate rigidly secured to said rotating part of the 50 lock inwardly of and overlying said first-mentioned plate and adapted to be connected to said valve, whereby rotation of said rotating part of the lock actuates said valve and said second-mentioned plate holds said 55 rotating part against movement outwardly of said body portion.

5. An actuating and locking mechanism of the character described including a body portion having an opening therein, a lock 65 including a casing mounted in said opening and having a rotatable part projecting beyond the end of said casing, a plate having an opening therein to receive said rotatable part fitted over the same between the end 70 thereof and said casing, a second plate rigidly secured to the projecting end of said rotatable part to hold said rotatable part against movement outwardly of said casing, and a third plate rigidly connected to said 75 second-mentioned plate and adapted to be connected to a member to be rotated.

CHARLES H. RUST.
